UNITED STATES PATENT OFFICE.

EVA C. LEONARD, OF THOMPSON, PENNSYLVANIA.

PORTABLE STOVE.

SPECIFICATION forming part of Letters Patent No. 707,243, dated August 19, 1902.

Application filed April 24, 1902. Serial No. 104,464. (No model.)

To all whom it may concern:

Be it known that I, EVA C. LEONARD, a citizen of the United States, and a resident of Thompson, in the county of Susquehanna and State of Pennsylvania, have invented certain new and useful Improvements in Portable Stoves, of which the following is a specification.

The object of my invention is to provide a portable sheet-metal stove which is particularly adapted for the purpose of heating flat-irons, but may be used also for light cooking, for heating a room, and for such other purposes for which a stove of this character is employed.

The invention contemplates the provision of an improved portable stove which can be manufactured and sold at small expense, which shall be light and durable in construction, and which shall be convenient in use.

The invention consists in the particular construction and arrangement of parts, all as hereinafter fully described, and specifically set forth in the appended claims.

In the accompanying drawings, which form a part of this specification, Figure 1 is a front elevation of a portable stove constructed in accordance with my invention. Fig. 2 is a plan view. Fig. 3 is a vertical sectional view. Fig. 4 is a horizontal sectional view.

Like letters of reference indicate like parts in the several views of the drawings.

The letter A designates the body of the stove, which is preferably rectangular or box shape, consisting of the front and back *a* and *a'*, respectively, the sides *a²* *a²'*, and bottom *a³*, the latter being curved upward at the corners of the front, as shown. To the four corners of the body A are attached feet *b*, which are preferably cast-iron and are adapted to support the stove a suitable distance above the floor. The sides *a²* are turned into a bead *c* at the top of the stove, said bead being reinforced by a wire *c'*, the ends of which rest upon the upper edge of the front and back, and from this bead the side pieces are extended horizontally to provide rails *c²*, which support the sliding sections of the top *a⁴* and also form supports for the flat-irons.

At a suitable distance from the bottom of the stove is a grate *d*, consisting of a metal plate perforated to permit air to pass to the

fuel, the said grate being supported upon rods *e e*, passed through the front and back *a* and *a'*. This grate is loosely supported on the rods, so that it may be tilted at any time to dump ashes from the same, and one of the supporting-rods is located a slight distance from the adjoining side to permit of this operation. By curving the forward corners of the bottom upward, as shown in Figs. 1 and 4, it not only facilitates the removal of ashes by preventing accumulation in said corners, but also the heat radiated by said curved corners will be directed out of the openings *a⁵* in the front of the stove.

In the front of the stove, below the grate, is a door *f*, provided with flanges *f'* and with a sliding damper *g*, which latter is adapted to supply the draft to the stove.

In the back of the stove is an opening *h*, near the top, into which a stovepipe may be inserted.

It will be understood that this stove is adapted to burn wood or charcoal, and after the fuel has burned to red-hot coals the said stove may be entirely closed and carried to any place desired and will throw off a great amount of heat. When the smoke-pipe is removed, the hole *h* is closed by a cap, and in order to facilitate carrying the stove it is provided with handles *i*.

It will be readily seen that I provide a simple, cheap, and effective stove, which may be used for different purposes, and being portable may be located in any convenient place in a room and may be also used advantageously for heating flat-irons either for ironing clothes or pressing garments.

A portable stove of this character will prove a very convenient device and will give a maximum heat from the fuel used.

Another important advantage is the fact that the stove can be manufactured and sold at small cost.

Having thus particularly described my invention, what I claim as new, and desire to secure by Letters Patent, is—

1. In a portable stove, the combination, of the sheet-metal body A, having a sliding top, and the bottom curved up at the corners of the front, a perforated plate forming the grate, rods supporting the grate and bearing at their ends in the walls of the body of the stove, and a

door in the front provided with a damper, the said stove being supported upon feet, substantially as shown and described.

2. In a portable stove, the combination, of 5 the body A made up of sheet metal and having a bottom curved upward at its front corners, a sliding plate forming the top of the stove, a perforated plate forming the grate and supported upon rods extending from the front to 10 the rear, one of the rods being located away from the adjoining side, and a door covering an opening in the front, said door having a sliding damper and inwardly-projecting flanges, substantially as shown and described.

15 3. In a portable stove, the combination, of the body A, made up of sheet metal and rectangular in cross-section, a bottom curved

upward at its front corners, openings through the body of the stove below said curved corners, the sides of the body of the stove being 20 turned into beads reinforced by wires which rest upon the front and back, and said sides extended to provide the flanges, and a sliding top supported upon said flanges; together with a door in the front of the stove having 25 flanges and a damper, the said stove being provided with supporting-feet, and with handles, as shown and described.

In testimony whereof I affix my signature in the presence of two witnesses.

EVA C. LEONARD.
